YARN CHANGER

Rudolph E. Zeruneith, Philadelphia, Pa.

Application April 6, 1954, Serial No. 421,355

2 Claims. (Cl. 66—138)

The present invention relates to the art of knitting and more particularly to yarn changer mechanism for a circular knitting machine whereby the yarns fed to the machine may be selectively changed.

It is an object of the present invention to provide a yarn changer of simplified construction wherein the parts used to selectively position the yarn fingers may be interchangeably used with any of the yarn fingers. It is also an object to provide finger-moving plungers which are in part supported by the yarn fingers. Furthermore the plungers, preferably similarly shaped, have their finger-moving ends supported at substantially a common level by the fingers while their movement-receiving ends are supported at a plurality of levels.

A further object is to provide plunger-holding latches to retain the fingers and the plungers in latched positions and to provide a single spring for each finger and its respective latch to maintain the fingers, plungers and the latches in their proper relative positions.

With the above and related objects in view as they may appear in the specification, the invention consists in the operation of and the construction and combination of parts as will be more fully understood from the following description thereof, when read in conjunction with the accompanying drawings.

Figure 1 is a view in side elevation of the improved 40 strip shown in position upon the strip-supporting bracket.

Figure 2 is a view in rear elevation of Figure 1.

Figure 3 is a view in front elevation of Figure 1 with the upper portion of the strip-supporting bracket removed.

Figure 4 is a top plan view of the strip without the strip-supporting bracket.

Figure 5 is a view in section of the strip taken lengthwise through the strip box and showing the three strip fingers, one of which is in yarn feeding position.

Figure 6 is a view similar to Figure 5 taken between the feeding-positioned strip finger and the adjacent strip finger.

The improved multiple-yarn strip or strip of the present invention, of general application to any type of knitting machine, is preferably used on a multiple feed circular rotary cam ring rib knitting machine of the type shown in co-pending application Serial No. 81,440, filed March 15, 1949 (on which patent-application Patent No. 2,705,410 was issued on April 5, 1955, wherein a strip is used at each feed to selectively change the yarns fed to the needles of the machine and wherein the yarn changing is initiated on the dial needles. The newly formed strip generally comprises a plurality of similarly shaped yarn-carrying fingers pivotally mounted in a housing for positive movement toward and spring urged movement from the needles, a like plurality of similarly shaped yarn-finger-moving plungers or push blades generally slidably mounted in the housing in individual association with the yarn fingers for positive movement to-

2

ward and spring urged movement from the yarn fingers, the positive movement of the plungers moving the fingers toward the needles, a like plurality of similarly shaped plunger-holding latches pivotally mounted in the housing 5 in individual association with the plungers for positive movement from spring urged movement toward the plungers, the latches holding the plungers in their finger-moving positions, and springs in individual association with the yarn fingers and their respective latches to provide the spring urged movements of the yarn fingers, the plungers and the latches.

The invention may be understood by referring to the drawings wherein a generally inverted U-shaped strip-housing 10 is provided to support the fingers, the plungers, the latches, and the springs of the strip, the housing 10 having a top 11 and side walls 12 and 13, the top and side walls being of generally common extent at the rear end of the housing 10 while the side walls extend beyond the top at the front end of the housing 20 to form ears 14.

The yarn carrying fingers, here shown as three in number although it will be understood that the strip may have a greater or a lesser number thereof, are relatively thin similarly shaped flat rectangular-like members, as indicated at 15, 16 and 17, each finger having a pair of aligned yarn-guiding holes 18 and 19 formed therein adjacent one of its longitudinal edges at either side of an undercut portion 20 of the finger. The fingers 15, 16 and 17 are pivotally mounted adjacent each other on a common pin 21 secured in and extending between the housing ears 14, forwardly of the top 11, the pin 21 passing through the fingers at one end thereof to one side of the holes 18. Each finger has a rounded-bottom plunger-supporting V-shaped notch 22 formed in its other longitudinal edge just below the pin 21. A tensioned spring 23, suitably secured to the said other longitudinal edge of each finger adjacent its yarn feeding hole 19, constantly urges its finger rearwardly of the housing 10 out of feeding position.

The finger-actuating plungers, one for each finger, are relatively thin similarly shaped flat strip-like members, as indicated at 24, 25 and 26, each plunger having its yarn-finger-contacting end rounded as at 27 and having its other end reduced in width to form a stop-shoulder 28. The plungers 24, 25 and 26 are generally slidably supported within the housing 10 in individual association with the fingers 15, 16 and 17 respectively, by the fingers themselves and by a rectangular plate 29 secured to the rear face of the housing. The plate 29, positioned in a vertical slot formed in the rear face of the housing 10, is secured to the housing by a screw 30 passing through the plate in threaded engagement with the top 11. Spaced angularly in the plate 29 is a series of three rectangular apertures 31, through which the shouldered ends of the plungers 24, 25 and 26 are adapted to extend, their shoulders 28 engaging the inner face of the plate 29 to provide movement-limiting stops for the plungers. The plungers 24, 25 and 26 are disposed so that their rounded ends 27 are received at substantially a common level by the notches 23 of their respective fingers while their shouldered ends extend through the plate apertures 31 to provide plunger-moving-butts 32, 33 and 34, respectively, at three separate levels. Inasmuch as the springs 23 urge the fingers rearwardly, the fingers in turn will urge the plungers rearwardly of the housing 10 where they will be stopped by the plate 29. The butts are adapted to be selectively engaged by appropriate strip-pattern mechanism, not shown, to positively move their plungers inwardly of the housing 10 against the action of springs 23, the plungers in turn positively moving their respective fingers about the pin

21 to yarn feeding position, the plunger 24 and the finger 15 being shown in forward position in Figure 5, there they will be held until such time as the yarns are changed. Each plunger has a latch-receiving notch 35 formed in its lower longitudinal edge adjacent the end 27 thereof, whereby the plungers may be held in their inward positions by suitable spring-urged latches.

The latches, one for each plunger, are also relatively thin similarly shaped flat strip-like members, as indicated at 36, 37 and 38, each latch having one end 39 cut to provide a plunger-notch-engaging corner 40 and having its other end 41 chamfered on its underside at 42. The latches 36, 37 and 38 are pivotally mounted adjacent each other within the housing 10 below and in individual association with the plungers 24, 25 and 26, respectively, on a common pin 43 secured in and extending between the housing walls 12 and 13, with the pin 43 passing through the latches at approximately one third their length as measured from their chamfered ends. The other ends of springs 23 are suitably secured to the lower longitudinal edges of the respective latches between their pivot points and their chamfered ends to provide for the spring urged movement of the fingers, plungers and latches. The corners 40 of the latches are spring urged to engage in the notches 35 of the inwardly moved plungers to so retain them in latched position, Figure 5, while the latch ends 39 are held in yielding engagement with the bottom face of the rearwardly positioned unlatched plungers between their notches 35 and their ends 27, Figure 6, ready for plunger-engaging action. The ends 41 of the latches extend beyond the rear of the housing 10 below the plate 29 where their chamfered surfaces 42 are in position for latch-tripping engagement with the latch releasing portion of appropriate stiper-pattern mechanism, not shown, to partially rotate all the latches to release any latched plungers. It will be understood that the tripping of any latch will cause its spring 23 to move the finger and plunger rearwardly of the housing 10 to idle position, the finger 16 and the plunger 25 being shown in such unlatched position in Figure 6. The latch ends 41 extend at a slight angle to the horizontal, Figures 5 and 6, inasmuch as each latch turns a different amount to cooperate at a separate level with each plunger. The normal action of stiper-pattern mechanism, as is well known in the art, is such that the selected plungers are held inwardly long enough, after all the latches have been tripped to release any latched plungers, to be latched by the now-free latches.

The stiper may be secured to the machine by means of an L-shaped stiper bracket 43 to one end 44 of which the stiper housing 10 is adjustably secured. The other end 45 of the bracket 43 is slidably mounted in a vertical slot formed in the outer peripheral face of a horizontal circular stiper-supporting ring 46, the ring being shown in my application, for vertical adjustment of the bracket 43 (and the stiper) relative to the needle circle of the machine. It will be understood that a number of stripers, one for each feed, may be similarly mounted at circumferentially spaced locations on the ring 46. Vertical adjustment of the bracket 43 may be made with a set-screw-headed screw 47 extending longitudinally from threaded engagement with the bracket end 45, the screw 47 being positioned so that the underside of its head may contact the upper face of the ring 46 to position the bracket 43 as the screw 47 is turned, after which the bracket 43 may be secured by a holding screw 48 which passes through a washer 49 and through an enlarged hole

50 in the bracket end 45 for threaded engagement with the ring 46. The housing top 11 is provided with an upwardly extending key-member 51 which is slidably mounted in a longitudinal slot in the underside of bracket end 44 for radial adjustment of the housing 10 (and the stiper) relative to the needle circle of the machine. Radial adjustment of the housing may be made by means of a set-screw-headed screw 52 extending longitudinally from threaded engagement with the rear of housing top 11 at one undercut side thereof, the screw 52 being so positioned that the underside of its head may contact the outer face of the bracket end 44 to position the housing 10 as the screw 52 is turned, after which the housing may be secured by a holding screw 53 which passes through a washer 54 and through an enlarged aperture 55 in bracket end 44 for threaded engagement with the housing top 11.

It will be seen that the present invention provides an improved multiple-yarn stiper or yarn changer wherein 20 similarly formed yarn fingers are positively moved in one direction against spring action by the positive movement of similarly formed plungers moved against the same spring action, wherein the fingers and their respective plungers are held in their positively moved positions by 25 similarly formed latches urged into contact with the plungers by the same spring action and wherein individual springs between each finger and its respective latch provides the spring action, the plungers having their movement receiving ends supported at separate levels 30 for engagement by the plunger-moving means, while their motion-transmitting ends are at substantially a common level in plunger-supporting engagement with the yarn fingers.

It will be understood that suitable clamp and cutter 35 may be secured to the stiper housing 10 to hold the idle yarn ends, and such a clamp and cutter is shown in my application which also shows the manner of securing the same to the stiper.

Having thus described the invention, it is claimed:

40 1. A yarn changer for a knitting machine, said yarn changer having a housing, a plurality of movable yarn fingers pivotally mounted in said housing, similarly formed strip-like finger-moving-plungers movably mounted in said housing in operative alignment and in individual association with the respective fingers, similarly formed strip-like plunger-holding-latches pivotally mounted in said housing in operative alignment and in individual association with the respective plungers, and a separate tension spring operatively interposed and connected to each of said fingers and its respective latch, and arranged to urge said fingers and their respective latches towards their respective plungers.

45 2. A yarn changer as set forth in claim 1 in which said plungers have one of their ends interengaged with said yarn fingers at substantially a common level for arcuate movement in relation thereto and have their other ends slidably supported by and projecting from said housing at a plurality of levels, and in which said housing has a stop to limit the projecting movement of said plungers therefrom, said fingers urging said plungers toward said stop and thereby retaining said plungers in said interengagement with said fingers.
